Des. 237,753
Patented Nov. 18, 1975

237,753

LIVE-BAIT PACK

Andrew O. Lightfoot, 2848 Bonnywood,
Dallas, Tex. 75233

Filed June 3, 1974, Ser. No. 475,527

Term of patent 14 years

Int. Cl. D3—02

U.S. Cl. D87—1 R

FIG. 1 is a front perspective view of a live-bait pack showing my new design;

FIG. 2 is a side elevational view thereof on a reduced scale;

FIG. 3 is a back elevational view; and

FIG. 4 is a bottom plan view.

I claim:

The ornamental design for a live-bait pack, substantially as shown and described.
